CAR CONSTRUCTION

George E. Dath, Mokena, Ill., assignor to W. H. Miner, Inc., Chicago, Ill., a corporation of Delaware

Application April 9, 1945, Serial No. 587,284

4 Claims. (Cl. 105—200)

This invention relates to improvements in car construction.

One object of the invention is to provide a locking center pin for railway cars, connecting the body and truck bolsters, comprising two elongated sections extending through the usual center pin receiving openings of the bolsters, each section being headed at opposite ends to shoulder against the bolsters at said openings, wherein the sections are held spread apart and in shouldered engagement with said bolsters by a laterally projecting enlargement on the inner side of each section bearing on the inner side of the other section, said enlargements being at opposite ends of the pin and the engagement being on flat vertical surfaces, thereby preventing accidental relative vertical displacement of the sections of the pin with respect to each other to an extent to allow collapse of the pin with resultant failure of the same performing its function of locking the bolsters together.

A more specific object of the invention is to provide a center pin as set forth in the preceding paragraph, wherein the lower end of the pin where it extends through the bearing opening of the truck bolster presents maximum resistance to transverse shearing forces by providing relatively large areas of contact between the sections thereof along the inner sides of said lower end portions.

Other objects of the invention will more clearly appear from the description and claims herein-after following.

In the drawing forming a part of this specification, Figure 1 is a vertical sectional view, lengthwise of a railway car, through the body and truck bolsters thereof, illustrating my improvements in connection therewith. Figure 2 is a view, similar to Figure 1, partly broken away, illustrating the manner of applying my improved locking center pin. Figure 3 is a side elevational view of the bottom end portion of my improved locking center pin, looking from right to left in Figure 1. Figure 4 is a top plan view of the improved locking center pin. Figure 5 is a bottom plan view of the improved locking center pin, looking upwardly in Figure 1.

In said drawing, 11 indicates the body bolster of the car and 12 the truck bolster. The body bolster includes the usual center sill structure 13 and diaphragm sections 14 extending from the sill at the body bolster portion thereof. The center sill is provided with the usual filler casting 15 having a center section 16 to accommodate the locking center pin. The section 16 is of cylindrical tubular form, as shown, and presents a

substantially flat, horizontal annular abutment shoulder 17 at its upper end surrounding the opening thereof, with which the headed upper end of the locking center pin cooperates.

The truck bolster 12 has top and bottom walls 18 and 19, connecting side walls 20, only one of which is shown, and spaced, laterally extending, vertical walls 21—21. The spaced walls 21—21 define a pocket 22 therebetween which serves to accommodate the bottom head of the center pin connecting the bolsters. The body bolster 11, including the center sill 13, is supported on the top wall of the truck bolster by means of the usual center plate 23 fixed to the body bolster, and which has a depending cylindrical bearing projection 24 seated in the bearing pocket provided by an upstanding annular rib 25 on the top wall of the truck bolster. The truck bolster is provided with a tubular sleeve section 26 formed by upstanding and depending annular flanges projecting from the top and bottom sides of the wall 18 of the truck bolster. The sleeve 26 is of the same diameter as the sleeve 16 of the body bolster and is in vertical alignment with the sleeve 16. The upstanding flange portion of the sleeve 26 extends into and has bearing engagement with a central pocket 27 of the center plate 23. The bottom end of the depending flange portion of the sleeve 26 presents a downwardly facing, annular abutment shoulder 28 surrounding the opening of the sleeve with which the head portion at the lower end of my improved locking center pin is adapted to cooperate. As shown most clearly in Figure 1, the bottom wall 19 of the truck bolster is provided with an opening 29 therethrough which communicates with the pocket 22 and through which the center pin is passed in applying the same to the body and truck bolsters.

My improved locking center pin serves to connect the body and truck bolsters of the railway car and lock the same against vertical separation, and comprises broadly two elongated sections or members A and B, which are headed at opposite ends.

The two members A and B are of the same design, except as hereinafter pointed out. Each member is of substantially semi-cylindrical cross section and is provided at the top thereof with an eccentric, substantially semi-cylindrical, outstanding flange 30 and with a concentric, substantially semi-cylindrical, outstanding flange 31 at the bottom end thereof. As will be evident, the flanges 30 and 31 form top and bottom head members of the members A and B, which are at

opposite ends of the shank portions of said members.

On the inner side, the member B presents a substantially flat, vertically extending, transverse face 32. At the upper end thereof, the member B has a laterally inwardly extending flange or lug 33 projecting from the face 32. The lug 33 has its top face in transverse alignment with the top surface of the flange 30 at the upper end of the member B and is cut away on an incline or beveled off at its underneath side, as indicated at 34. The transverse, vertical side face of the lug 33 is substantially flat and in the applied condition of the pin bears flatly on the inner side face 35 of the head formed by the flange 30 at the upper end of the member A.

The member A is laterally inwardly enlarged at its lower end, as indicated at 36, said enlarged portion presenting a vertically extending, substantially flat, transverse surface 37 adapted to bear flatly on the inner face 32 of the member B. The inner side of the member A above the surface 37 is inclined away from the inner side of the member B, that is, the inner side of the member A presents an inclined surface 38 on its inner side which extends approximately to the flange 30 at the upper end of said member A where the member A presents the vertical flat face 35 hereinbefore referred to. At the upper end at the inner side thereof, the member A is beveled or inclined, as indicated at 39, to facilitate assembling of the pin with the bolster, the beveled face 39 cooperating with the beveled face 34 of the lug 33 of the member B to cam or spread the members A and B apart at their upper ends and bring the flange 30 of the member A into overhanging relation with the shoulder 17 of the body bolster.

As will be evident upon reference to Figures 1 and 2, the vertically extending surface 37 of the enlarged portion at the lower end of the member A extends upwardly a considerable distance into the sleeve 26 of the truck bolster well beyond the plane of the bearing connection between the center plate of the body bolster and the truck bolster and has true flat bearing engagement throughout its height with the inner flat face 32 of the member B, thereby greatly strengthening the lower portion of the assembled pin to resist transverse shear at the bearing connection between the bolsters.

The eccentric flanges 30—30 at the top ends of the members A and B are of such a size that they will pass freely through the pin receiving openings of both the body and truck bolsters when the pin is contracted, that is, the top head of the member B is of such a size and outside contour that it will pass freely upwardly and downwardly through the center pin receiving openings of the bolsters when the member A is absent, and the head of the member A is of such a size and outside contour that it will pass freely through said openings when the member A is inclined and the pin is contracted with the member B in the position shown in Figure 2.

Each member A and B is preferably provided with a depending, perforated ear 40 at its lower end adapted to receive a cotter pin 41. The cotter pin 41 when engaged through the ears 40—40 holds the two members A and B against vertical separation.

In applying my improved locking center pin to the bolsters, the member B is first inserted in the center pin openings of the bolsters by passing the same upwardly through said openings

until the upper head or flange 30 thereof reaches a position above the shoulder 17 of the body bolster. When thus disposed, the member B is displaced laterally outwardly to engage the flange 30 thereof over said shoulder, as shown in Figure 1, and the flange 31 beneath the shoulder 28 of the sleeve 26 of the truck bolster. The member A is then inserted upwardly in the bolster openings and inclined, as shown in Figure 2. As the member A is pushed upwardly, the upper end thereof engages the lug 33 of the member B, thereby lifting the latter, as shown in Figure 2, until the lower edge of the head 30 of the member A reaches a point above the shoulder 17. Upon further upward displacement of the member A, the latter is forced laterally outwardly by camming engagement of the faces 38 and 34, thereby bringing the flange 30 of the member A over the shoulder 17. The members A and B are then permitted to drop to the position shown in Figure 1 and may be locked together by the cotter pin 41. As will be evident, in the assembled condition of the pin, the upper end of the pin is held spread apart by the lug 33 while the lower end is held in expanded condition by the enlarged portion 36 of the member A abutting the inner side face 32 of the member B.

While the members of the locking center pin are preferably locked together by the cotter pin 41, it will be evident that the latter may be omitted, inasmuch as with the heads 30—30 at the upper end of the members A and B resting on the shoulder 17 of the body bolster, the pin will be maintained in the spread condition shown in Figure 1, locking the bolsters together, the weight of the member B effectively preventing the same from working upwardly to a position where the upper head of the member A could slip below the lug 33 of the member B.

In removing the locking center pin from the bolsters, the operation is substantially the reverse of that just described, the member B being pushed upwardly until it provides sufficient clearance for the head 30 of the member A to pass beneath the lug 33, as shown in Figure 2, so that the member A may drop out or be pulled forcibly downwardly.

As will be evident from the preceding description taken in connection with the drawing, in my improved design of center pin construction, advantage is taken of the usual play or clearance provided between the heads of the pin and the shoulders of the bolsters to permit relative longitudinal displacement of the members of the sectional pin in assembling the same with the bolsters. It is further pointed out that by so designing the pin that the members composing the same are insertable within the center pin receiving openings of the bolsters, one at a time and in succession, and taking advantage of the usual clearance or play provided between the shoulders of the bolsters and the heads of the members of the pin, the number of members making up the complete expandible pin may be reduced to a minimum, or two in number, and yet give the maximum overlap of the heads with respect to the shoulders at the pin receiving openings of the bolsters to provide the required strength.

I claim:

1. In car construction, the combination with body and truck bolsters having bearing engagement with each other on a horizontal plane and provided with vertically aligned, center pin receiving openings; of a two-part sectional center pin insertable in said openings, one of said parts

comprising an elongated member having heads at the top and bottom ends, said member having a flat vertical inner side face and a laterally inwardly offset enlargement extending from said side face at the upper end of said member, said enlargement having a vertical inner side face, the other of said parts comprising a second elongated member having heads at the top and bottom ends, said second member increasing in thickness toward its lower end and having vertical flat inner side faces at its upper and lower ends connected by an elongated inclined inner side surface, said lower vertical side face extending from the lower end of said member upwardly beyond the horizontal plane of bearing engagement between said bolsters, and bearing on the flat vertical inner side face of said first named member, said upper vertical face of said second named member abutting the vertical inner side face of the enlargement of said first named member.

2. In car construction, the combination with body and truck bolsters having bearing engagement with each other on a horizontal plane and provided with vertically aligned, center pin receiving openings; of a two part sectional center pin insertable in said openings, one of said parts comprising an elongated member having heads at the top and bottom ends, said member having a flat vertical inner side face and a laterally inwardly offset enlargement extending from said side face at the upper end of said member, said enlargement having a vertical inner side face and an inclined underneath edge face, the other of said parts comprising a second elongated member having heads at the top and bottom ends, said second member increasing in thickness toward its lower end and having vertical flat inner side faces at its upper and lower ends connected by an elongated inclined inner side surface, said lower vertical side face extending from the lower end of said member upwardly beyond the horizontal plane of bearing engagement between said bolsters, and bearing on the flat vertical inner side face of said first named member, said upper vertical face of said second named member abutting the vertical inner side face of the enlargement of said first named member, said second named member having the inner upper corner thereof beveled, said beveled portion being engageable with said inclined underneath edge face of the enlargement of said first named member to cam the upper ends of said members apart upon relative lengthwise displacement of said members with respect to each other.

3. In car construction, the combination with a body bolster provided with a center plate element; of a truck bolster having bearing engagement with said center plate element on a horizontal plane, said bolsters having aligned center

pin receiving openings; and a two-part sectional center pin insertable in said openings, one of said parts comprising an elongated member having heads at the top and bottom ends, said member having a flat vertical inner side face and a laterally inwardly offset enlargement extending from said side face at the upper end of said member, said enlargement having a vertical inner side face, the other of said parts comprising a second elongated member having heads at the top and bottom ends, said second member increasing in thickness toward its lower end and having vertical flat inner side faces at its upper and lower ends connected by an elongated inclined inner side surface, said lower vertical side face extending from the lower end of said member upwardly beyond the horizontal plane of bearing engagement between said center plate and truck bolster, and bearing on the flat vertical inner side face of said first named member, said upper vertical face of said second named member abutting the vertical inner side face of the enlargement of said first named member.

4. In car construction, the combination with a body bolster provided with a center plate element; of a truck bolster having bearing engagement with said center plate element on a horizontal plane, said bolsters having aligned center pin receiving openings; and a two part sectional center pin insertable in said openings, one of said parts comprising an elongated member having heads at the top and bottom ends, said member having a flat vertical inner side face and a laterally inwardly offset enlargement extending from said side face at the upper end of said member, said enlargement having a vertical inner side face, and an inclined underneath edge face, the other of said parts comprising a second elongated member having heads at the top and bottom ends, said second member increasing in thickness toward its lower end and having vertical flat inner side faces at its upper and lower ends connected by an elongated inclined inner side surface, said lower vertical side face extending from the lower end of said member upwardly beyond the horizontal plane of bearing engagement between said center plate and truck bolster, and bearing on the flat vertical inner side face of said first named member, said upper vertical face of said second named member abutting the vertical inner side face of the enlargement of said first named member.

5. In car construction, the combination with a body bolster provided with a center plate element; of a truck bolster having bearing engagement with said center plate element on a horizontal plane, said bolsters having aligned center pin receiving openings; and a two part sectional center pin insertable in said openings, one of said parts comprising an elongated member having heads at the top and bottom ends, said member having a flat vertical inner side face and a laterally inwardly offset enlargement extending from said side face at the upper end of said member, said enlargement having a vertical inner side face, and an inclined underneath edge face, the other of said parts comprising a second elongated member having heads at the top and bottom ends, said second member increasing in thickness toward its lower end and having vertical flat inner side faces at its upper and lower ends connected by an elongated inclined inner side surface, said lower vertical side face extending from the lower end of said member upwardly beyond the horizontal plane of bearing engagement between said center plate and truck bolster, and bearing on the flat vertical inner side face of said first named member, said upper vertical face of said second named member abutting the vertical inner side face of the enlargement of said first named member.

GEORGE E. DATH.
